UNITED STATES PATENT OFFICE.

KEN E. ROCHEL, OF GALVESTON, TEXAS.

RAIL.

1,114,527.

Specification of Letters Patent. Patented Oct. 20, 1914.

Application filed November 29, 1913. Serial No. 803,781.

To all whom it may concern:

Be it known that I, KEN E. ROCHEL, a citizen of the United States, residing at Galveston, in the county of Galveston and State of Texas, have invented new and useful Improvements in Rails, of which the following is a specification.

The present invention relates to improvements in railway rails, the object being to provide a hollow rail having simple and cheap, but effective, means for connecting the ends of the rails, to provide a joint for the rails, and the improvement resides in the construction, combination and arrangement of parts set forth in the following specification and falling within the scope of the appended claim.

In the drawing: Figure 1 is a perspective view of rails constructed in accordance with the present invention, one of the rails being arranged upon the joint, and the second rail end about to be positioned upon the joint, and Fig. 2 is a sectional view on the line 2—2 of Fig. 1.

The rails are designated by the numerals 1, each comprising a hollow member that includes a vertical inner side 2 which has its lower end provided with an outturned horizontally disposed flange 3, and its upper portion provided with a horizontally straight head 4. The outer side 5 of each of the rails extends at an angle from the head and terminates in a foot or flange 6 which is horizontally straight and which is disposed in the same plane with the opposite foot or flange 3 of the side 2. The head may be of a greater thickness than the sides 2 and 5, and the wall of the head between the inner faces of the sides 2 and 5 is preferably rounded, as indicated by the numerals 7. The sides of the rail are not at any point provided with openings but the foot and flanges 3 and 6 respectively are formed with vertical openings at suitably spaced intervals and at the ends of the rail, the said openings being adapted to register with similar openings in the angularly disposed horizontally straight feet 8 and 9 provided upon the joint member 10. The joint member 10 is hollow, and has its opposite and upper portions agreeing in shape with the

inner faces of the sides and the head of the rails 1, the feet 8 and 9 being engaged by the flanges 3 and 6 of the rails. The openings in the feet of the joint member and in the horizontally disposed flanges 3 and 6 of the rail members are adapted to register and to receive the shanks of bolts which extend upwardly from the under faces of the feet 8 and 9, the upper projecting ends being secured by suitable nuts, as illustrated in the drawings. The rails are secured to the ties T through the medium of the usual spikes S, and the said rail members adjacent the joints are supported upon elevated ties, or ties arranged above the level of the ties upon which the joints for the rails are assembled.

From the above description, taken in connection with the accompanying drawings, the simplicity of the device as well as the advantages thereof will, it is thought, be perfectly apparent to those skilled in the art to which such inventions appertain without further detailed description.

Having thus described the invention, what I claim is:

In combination, a pair of rails, each comprising a vertically straight side having its lower edge provided with a horizontally straight outwardly disposed flange, the said side terminating in a horizontally straight head, the outer wall of each rail being inclined outwardly and downwardly and terminating in an angular flange which is horizontally straight and which is disposed in the same plane of that of the first mentioned flange, a hollow joint member having its contour shaped to correspond with the inner contour of the rails and provided with outturned feet which are adapted to underlie the flanges of the rails, the flanges and feet being provided with registering openings, and securing elements passing through the openings for preventing relative movements of said rails and hollow joint member.

In testimony whereof I affix my signature in presence of two witnesses.

KEN E. ROCHEL.
